UNITED STATES PATENT OFFICE.

GEORGE HEBER CARTER, OF RICHMOND HILL, NEW YORK.

FOUNTAIN-PEN.

1,030,502.

Specification of Letters Patent. Patented June 25, 1912.

Application filed October 17, 1910. Serial No. 587,532.

To all whom it may concern:

Be it known that I, GEORGE HEBER CARTER, a subject of the King of Great Britain, residing at Richmond Hill, in the county of 5 Queens and State of New York, have invented certain new and useful Improvements in Fountain-Pens, of which the following is a specification.

My invention relates to fountain pens, 10 and particularly to that class of such pens as contain within themselves the means whereby they may be refilled with ink, and which are called "self-filling" fountain pens. The preferred type of such pens in 15 connection with which I desire to employ my invention, is that wherein the cap of the pen acts as an exterior piston to draw the ink into the barrel through the nozzle.

The object of my invention is to produce 20 a simple and economical construction of such device and one that shall be certain in operation and will easily permit cleansing.

Other objects are to insure that the refill 25 bore shall be automatically closed when the pen has received its load of ink; also to prevent any leakage of ink when the suction of the piston is released.

These and other objects which will appear as the specification proceeds, I attain 30 by the use of the devices illustrated in the accompanying drawings, wherein is represented a desirable form in which my invention may be embodied.

In the said drawing Figure 1 is a longitudinal view of a fountain pen illustrating 35 my invention as applied thereto, parts being illustrated in section. Fig. 2 is a detailed view illustrating in section the preferred form of my invention. Fig. 3 is a 40 similar view illustrating a slight modification therein. Fig. 4 is a view similar to Fig. 3 illustrating the parts in a different position. Fig. 5 is a cross-section on the line 5—5 of Fig. 2. Fig. 6 is a cross-section 45 on the line 6—6 of Fig. 2. Fig. 7 is a plan view of the valve-retaining means and the seat for the seal.

In carrying my invention into effect I employ a valve which will easily yield to 50 open the bore and which will automatically seat itself and close the bore when the pen has been filled with ink by the action of the piston, and in connection with the said valve I provide means whereby the ink will cause 55 the seating of the valve, and also prefer to employ means whereby the valve is always

retained in position. In connection with said valve I also employ a suitable seal whereby when the pen is in use the air will be excluded from admission to the upper 60 end of the barrel and thereby prevent bleeding of the pen, and the said seal is conveniently seated by the ordinary end plug of the pen. As convenient refilling means I prefer to employ the cap of the pen which 65 is illustrated as adapted to such use in my application, Serial No. 523,963, filed October 22, 1909, and allowed July 1, 1910, and in connection therewith some improvements are herewith provided. 70

The particular form in which my invention is illustrated in the present application comprises a valve A which I prefer to employ in the tapered form illustrated, as thereby a more certain closing of the bore 75 B is effected. The said bore is likewise tapered and is so trued down as to insure a fit with the valve A. Attached to the valve A, I preferably place a stem a which is sufficiently smaller than the reduced end 80 portion of B so that it shall pass easily through the bore and permit air to pass around its sides. Upon the upper end of the stem A is produced an enlarged retaining bulb a¹ which is too large to pass 85 through the bore B and therefore retains the valve A in place. The valve A and its stem a and the retainer a¹ may be all made of one piece of any suitable substance such as brass, and the retainer a¹ may be conveniently formed upon the stem A by enlarging the end thereof after it is inserted in place as by pressure from a pair of pliers. Attached to the valve A is a float C which 90 may be of any suitable substance which will be raised by the ink when the barrel is filled and thereby seat the valve. For this purpose cork or very light wood may well be employed. Suitable means are provided for closing the bore airtight when the pen 95 is filled and in use, and as illustrated in Fig. 2, such means comprise a seal D which has an annular bore d in which the stem and retainer are received when the pen is filled as illustrated in Fig. 1. The 100 lower face of the said seal D is received against an annular ring d¹ which I prefer to make compressible and which for this purpose may be made of soft rubber. This seal has its lower walls trued so that they 105 shall fit accurately upon the ring d¹ and which in turn is seated upon the sealing seat

110

2

5   *b* which surrounds the bore *B*. The said seal is loose so that it shall easily yield to permit the passage of air in filling the pen. The seal is seated and caused to seat the ring *d*¹ by end plug *E* which has a threaded stem *e* which screws into the threaded end of the barrel *F*. This threaded stem is likewise provided with a longitudinal air channel *e*¹. Upon the periphery of the barrel is situated a packing *f* for insuring a tight fit with the cap *G*, and this packing is conveniently made of cork or soft rubber or other suitable material. A retaining and enlarging ring *f*¹ is threaded onto the periphery of the barrel and serves to hold the packing *f* in place and when desired by screwing down on the said ring, the packing may be enlarged so as to maintain its fit with the cap. In operation in connection with this form of my invention, the end plug *E* is loosened up slightly, thereby relieving the seal *D* from pressure and permitting the same to spring upward. This will cause the ring *d*¹ to be held loosely on its seat, and the cap *G* being applied and the perforation *g* therein closed by the finger after it is pushed inward, and the nozzle of the pen being inserted in the ink, the said cap may be drawn up by hand, 30 whereupon the air from the interior of the pen will be drawn out by the piston through the bore *B* around the ring *d*¹ and seal *D* through the channel *e*¹ in the end plug. This will continue until the ink shall reach 35 the float *C*, whereupon the said float will be raised and will seat the tapered valve *A* in the bore *B*, preventing any further drawing in of ink. The cap *G* may then be withdrawn whereupon the seal *D* will automatically be seated by atmospheric pressure and will prevent the leakage of ink at the nozzle end of the pen. The end plug *E* may thereupon be screwed down until it presses upon the seal *D*, whereupon the said seal 40 will be forced against the ring *d*¹ compressing the same and effectually holding the seal *D* in place. When the plug *E* has been turned to its place, the upper end of the chamber *d* will contact with the bulb enlargement *a*¹ and unseat the valve *A*. The entrance of the air to the rear end of the barrel will thereby be prevented and ink 45 may be used from the nozzle without bleeding.

50   55   A modified form of my invention is illustrated in Figs. 3 and 4. In this form the seal *D* is seated directly upon the seat *b* and the soft ring *d*¹ is omitted. The said seal is retained in position by a washer *d*² which may well be made of hard rubber and which has parallel slots *d*³ for inserting and removing it. This washer is threaded exteriorly and is received in the threaded end bore of the barrel. It has a loose fit with 60 its thread and when the plug *E* is inserted

its stem *e* bears against the said washer which has sufficient play to press the seal *D* firmly to its seat. When the plug *E* is loosened up the said washer springs slightly permitting the seal *D* to rest with sufficient 70 looseness on its seat so that the air will pass around the same when the cap *G* is used as a piston. In this form the valve is not unseated by the seal *D* but it may be unseated if it sticks by applying the cap *G* with the perforation *g* closed, whereupon the air will force the valve *A* from its seat. This operation may also be employed in connection with the device illustrated in Figs. 1 and 2 if desired. In this form also the seal *D* 80 will automatically close the rear end of the bore and prevent leakage at the nozzle when the cap *G* is opened or withdrawn. For the seal and its retaining washer and the end plug, I prefer to employ hard rubber which 85 is well adapted to this purpose. I prefer to employ the perforated cap *G* for the reasons stated in my former application, to wit: That the said cap may be applied to the rear of the barrel and forced to its inner- 90 most position with the perforation open whereby any ink remaining in the barrel of the pen will not be forced out, and upon closing the said perforation the barrel acts 95 as an exterior piston to fill the pen with ink.

In all the forms in which I have illustrated my invention the parts may easily be cleaned by forcing the cap *G* up and down with the perforation *g* closed, whereupon if the nozzle is immersed in water the said 100 water will be pumped in and out and will effectually clean the barrel. The rear parts may also be cleaned by removing the end plug *E* whereby, in the form illustrated in Figs. 1 and 2, the seal *D* and ring *d*¹ may 105 be lifted out for cleaning, or in the form illustrated in Fig. 3 the washer *d*² may be unscrewed and the seal *D* may then be taken out for cleaning.

Although I have described with great 110 particularity the construction of my pen, I do not regard it as necessarily limited to the precise shape or form or construction of the parts illustrated, nor yet to the particular material stated, as equivalents therefor 115 may be substituted within the limits of the appended claims without departing from the invention.

What I claim is:—

1. In a fountain pen, a barrel provided with a tapered bore at its rear end, a tapered valve adapted to close said bore, a stem on said valve of less size than said bore, and a support on said stem, a seal recessed to receive said stem and a seat therefor in said 125 barrel, and means for holding said seal to its seat.
2. In a fountain pen, a barrel provided with a tapered bore at its rear end, a tapered valve adapted to close said bore, a stem on 130

said valve of less size than said bore, and a support on said stem, a float carrying said valve, an automatically acting seal adapted to close the outer end of said bore, and a seat therefor in said barrel at the smaller end of said bore, and means for holding said seal to its seat.

3. In a fountain pen, a barrel provided with a tapered bore at its rear end, a tapered valve adapted to close said bore, and means for preventing the withdrawal of said valve from said bore, a float carrying said valve, an automatically acting seal adapted to close the outer end of said bore and a seat therefor surrounding the reduced end of said bore, and means for holding said seal to its seat.

4. In a fountain pen, a barrel provided with a tapered bore at its rear end, a tapered valve adapted to close said bore, a float carrying said valve, and a support for said valve adapted to prevent its withdrawal

from said bore, a seal adapted to close the outer end of said bore and a seat therefor at the reduced end of said bore, and a screw ²⁵ plug adapted to close the rear end of the barrel and hold the seal to its seat.

5. In a fountain pen, a barrel having a tapered bore, a tapered valve, a stem thereon and an enlargement on said stem adapted to prevent the withdrawal of the valve from said bore, a float attached to said valve, a seal and an expansible packing between same and said bore, and a threaded plug adapted to close the end of the barrel and ³⁰ ³⁵ hold said seal to its seat.

In witness whereof, I have hereunto signed my name in the presence of two subscribing witnesses.

GEORGE HEBER CARTER.
